UNITED STATES PATENT OFFICE

EDWIN W. WEBB, OF CHICAGO, ILLINOIS, ASSIGNEE TO STANDARD CAR TRUCK COMPANY, OF CHICAGO, ILLINOIS, A CORPORATION OF NEW JERSEY

SIDE BEARINGS FOR CARS

Application filed December 1, 1930. Serial No. 420,241.

My invention relates to side bearings for railway cars, and while it is capable of general application to both passenger and freight cars, it is especially well adapted for 5 use on passenger cars having six-wheeled trucks; and it has for its object to provide certain improvements in this class of bearings, with a view of securing increased convenience and efficiency.

More specifically stated, my present invention has for its object to provide certain improvements in those types of side bearings for railway cars disclosed and claimed in my own prior U. S. Patent 1,149,234, of August 10th, 1915, and in the U. S. patent to Lee W. Barber and myself, 1,763,081, of June 10th, 1930, both of which patents were issued to the Standard Car Truck Company of Chicago, Illinois, as the assignee of the above named applicants.

To the ends above stated, my invention consists of the novel devices and combinations of devices hereinafter described and pointed out in the claim. The invention is illustrated 25 in the accompanying drawings, wherein like notations refer to like parts throughout the several views:—

Fig. 1 is a plan view showing a part of the car body bolster or underframe of the 30 car and a part of the car truck, with some portions removed and others broken away;

Fig. 2 is a view chiefly in side elevation, but partly in vertical section of the same parts as shown in Fig. 1;

Fig. 3 is a view chiefly in vertical section on the line 3—3 of Fig. 2, with some parts broken away and one of the car wheels and axles shown in elevation;

Fig. 4 is chiefly a vertical section on the 40 line 4—4 of Fig. 1, with some parts broken away;

Fig. 5 is a horizontal section on the irregular line 5—5 of Fig. 4, thus affording practically a plan view of the supplemental housing in which the roller is journaled; and,

Fig. 6 is a perspective view, on a smaller scale, showing the roller carrier, or supplemental housing detached.

The numeral 6 represents one of the axles, 50 and 7, one of the wheels of the car. The nu-

meral 8 represents the body portion, and the numeral 9, one of the upwardly and outwardly extended curved arms of the truck bolster, which parts, 8 and 9, are cast integral with each other. Said body portion 8 is provided with the usual central circular housing 8a for the lower member 10 of the center plates. Said truck bolster arms 9 are provided, on the faces of their outer end portions, with tread plates 11 for the side bearing rollers which will presently be noted.

The numeral 12 represents the central portion of the car body bolster; the numeral 13 represents the laterally extending transoms of said body bolster; and the numeral 14 represents one of the longitudinal arch bars, or longitudinal connections which connect the pair of bolster transoms 13, substantially on lines which overlie the car wheel treads when the car is moving on a straight section of the track. The numeral 15 represents one of the central lateral webs which connect said arch bars 14 with the central part or body portion 12 of said car body bolster. All of said parts 12, 13, 14 and 15 constitute an integral casting which affords the body bolster portion of the underframe of the car body; and the central downwardly extended portion 12 thereof is provided with the upper, or male member 16 of the center plates which provide for the swiveling motion of the truck relative to the body of the car.

The above described cast metal truck bolster and the above described cast metal body bolster are now standard equipment for passenger cars.

Directing attention now to my improvements, the arch bars 14 of the body bolster are so constructed as to afford inverted U-shaped main housings 17 which project laterally outward from the central portions of said arch bars 14, measured lengthwise of the car, the centers of the said housings 17 being located on the cross central line through the center plate of the body bolster or under frame of the car, as best shown in Figs. 1, 2 and 3 of the drawings. Being formed, as just described, these main housings 17 are open at their outer ends, and open at their bottoms, and afford pockets adapted to receive the body portion

of the supplemental housing or roller carrier which will next be noted. The numeral 18 represents the body or hub portion of this roller carrier, or supplemental housing, and the numerals 19 represent the flanges of the same. The main housings 17 formed on the body bolster are provided with foot flanges 17a, which the flanges 19 of the roller carrier, or supplemental housing, joint or abut, or 10 might abut when the parts are in working position.

The numeral 20 represents one of the side bearing rollers having an axial bore, and the numeral 21 represents a central pin which 15 passes through the axial bore of the roller 20, has its ends projecting into laterally extended central portions of the body portion 18 of the supplemental housing, as bearings, and is fixed therein by a fastening pin 22, as best 20 shown in Figs. 3, 5 and 6. In other words the pin 21 does not turn in its said bearings, but, on the contrary, the roller 20 turns on the pin 21 as its journal.

The body portion 18 of said supplemental 25 housing, or roller carrier is of such shape as to afford, in its bottom, a central opening 23 of sufficient length and width to permit a portion of the periphery of the roller to protrude below the bottom of said supplemental housing far enough to contact with the tread plate 11 on the truck bolster 9, without bringing the supplemental housing or roller carrier into contact with that tread plate. The vertical walls of said opening 23, in the bottom of the 30 roller carrier or supplemental housing, have roller abutting faces of concave form approximately to the same arc as the periphery of the roller, but spaced apart therefrom far enough to permit clearance and the escape of 35 dust or dirt; and they extend downward and inward below the joint flanges 19 in position to contact with the tread plate 11 of the truck bolster, if the roller journaling pin 21 should happen to break in the service. The cross 40 section of said opening 23 in the bottom of the supplemental housing or roller carrier, is of less length than the diameter of the roller 20, and hence, it follows that, if the journaling pin 21 should break, in the service, the roller 45 20 could not fall out from its carrier or supplemental housing, but would be retained on the concave walls of the opening 23. From the foregoing, of course, it further follows that the portion of the periphery of the roller 50 20 which protrudes, is less than a half circle in arcuate length. The body portion 18 of said roller carrier or supplemental housing is of such shape, and the roller 20 is journaled 55 therein in such a way, that the said body portion and roller can be entered endwise of the roller into the housing 17 through the open end of the same and be detachably secured to the said housing and the car body bolster by the nutted bolts 25, and then all the parts will 60 be in working position, and the supplemental 65

housing will not only hold the roller in proper working position but will form substantially a closure to the open end and open bottom of the said main housing 17. Instead of the above stated direct connection, between the 70 supplemental and main housings, I prefer to apply sound deadening pads 24 between the joint flanges 17a and 19 of the said housing members, as shown in Fig. 4, and then, to fasten all of the said parts together by the 75 nutted bolts 25, as shown in the said view. The pads 24 may be composed of rubber, or other non-ferrous material adapted to cushion the vibrations of the metallic parts and deaden the noise that would otherwise be produced. 80

From the foregoing, it is obvious, that, for cars having truck bolsters equipped with the tread plates 11 and body bolsters equipped with main roller housing 17, all that will 85 need to be supplied to complete the needed side bearings are the supplemental housings or roller carriers above described; and if the sound deadening feature is desired, the pads 24 may also be supplied; and the said roller carrier or supplemental housing and pads 90 can be applied in proper working positions, without requiring any special adjustment of the car body in respect to the car truck, when the car is standing on a straight section of the track; and this is a great convenience in 95 the handling of cars in the service for replacements and repairs; and this is a matter of large importance, especially in respect to passenger cars, because of the fact that the tread plates on the truck bolster and the roller side bearings on the body bolster are located so far inward toward the cross centers of said bolsters and the car. This location makes the said parts difficult of access and the space for vertical adjustment is very limited unless the car body can be jacked up above the truck. The practicability and utility of my improvements disclosed and 100 claimed have been demonstrated by the actual commercial usage thereof on cars. 110

It must be obvious that the single piece casting made up of the parts 12, 13, 14, 15 and 17 constitute the underframe of the car body and that the partial side bearing housing 17 projecting outward from the profile faces of the arch bars 14, directly opposite the central webs 15, are supported on the cantilever principle from the strongest part of said frame. This is a structure which, so far as we know, is new over the entire prior art 115 and is one which has proven of great value in commercial service. 120

It must, of course, be understood, that more or less of the details and the forms and proportions of the various parts might be changed without departing from the spirit of my invention herein disclosed and claimed. 125

What is claimed is:

A one-piece cast metal underframe for a 130 car body, which frame has a central body

portion of the proper depth to support said frame at the proper height above the truck bolster, a pair of longitudinal main webs located, one on each of the opposite sides of the longitudinal center line of said frame, a pair of transoms connected with the opposite ends of said main webs, and extending laterally outward beyond the same, a pair of arch bars connecting said transoms inward of their outer ends, a pair of central cross webs extending laterally in opposite directions from said central portion of the frame to said transoms, on the cross central line of said frame, and a pair of partial housings for side bearings cast integral with and projecting laterally outward from the outer profile faces of said arch bars, whereby said partial housings for side bearings are supported on the cantilever principle from the strongest part of said frame.

In testimony whereof I affix my signature.
EDWIN W. WEBB.
